(57) **CLAIM**

We claim the ornamental design for a wristband for fitness monitoring capsule, as shown and described.

DESCRIPTION

FIG. 1 is a front view of a wristband for fitness monitoring capsule.

FIG. 2 is a left side view of the wristband of FIG. 1.

FIG. 3 is a rear view of the wristband of FIG. 1.

FIG. 4 is a right side view of the wristband of FIG. 1.

FIG. 5 is a bottom view of the wristband of FIG. 1.

FIG. 6 is a top view of the wristband of FIG. 1.

FIG. 7 is an isometric view of the wristband of FIG. 1; and, FIG. 8 is an isometric view of the wristband of FIG. 1 with the straps of the wristband clasped together to form a loop that may be worn about a person's wrist.

FIGS. 1 through 8 are drawn to-scale within each Figure, although the scale from Figure to Figure may vary.

Stipple shading is used in the accompanying Figures to convey surface contouring, not texture. Features depicted using broken lines and a lack of shading indicate environmental structure that is unclaimed in various embodiments. For example, various logos and other text are shown in broken lines and with a lack of shading; in such cases, the unshaded regions around such logos or text are enclosed in a rectangular border that represents the boundary between a claimed portion of the depicted design and the unclaimed portion of the depicted design.
